UNITED STATES PATENT OFFICE.

LIPA POLINKOWSKY, OF NEW YORK, N. Y., ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

1,365,270.

Specification of Letters Patent. Patented Jan. 11, 1921.

Application filed May 2, 1919. Serial No. 294,245.

To all whom it may concern:

Be it known that I, LIPA POLINKOWSKY, a citizen of Russia, residing at New York, in the county of New York, State of New

5 York, have invented certain new and useful Improvements in Telephone-Exchange Systems, of which the following is a full, clear, concise, and exact description.

This invention relates to telephone exchange systems in which connections between subscribers' lines are established by means of machine switching apparatus.

More particularly it relates to a system of this character in which the subscribers' lines 15 are provided with toll devices, such as coin collectors or message registers, operated by mechanism associated with and controlled by the switching apparatus to make a charge against calling subscribers' lines of all calls 20 that have been successfully completed.

The object of the invention is to provide, in a machine switching telephone system, the subscribers' lines with toll devices with operating means therefor, and which operating means is arranged to cause the proper 25 operation of said toll devices, according as a call succeeds or not, under the control of mechanism adapted to control the selective switches in the exchange.

30 A feature of the invention consists in providing a plurality of operating sources for the toll devices on the subscribers' lines, together with means controlled by certain controlling apparatus associated with the selective switches, for determining which of said sources shall be effective to operate the toll device, dependent upon whether or not the call succeeds.

A further feature consists in the provision 40 of a plurality of operating sources for the toll devices, with means for determining the selection of said operating sources, and which means is controlled by mechanism used for controlling the selective operation 45 of the selective switches during the time such mechanism is restoring to its normal position on the release of a connection.

A still further feature of invention, in a system of this type where controlling 50 switches are employed to control the operation of the selective switches, is the provision of toll devices such as coin collectors at the substations, together with two sources of current, one for operating the coin collector to cash the coin and the other to return

the coin, and means under the control of said controlling switches during release for selecting one or the other of said current sources.

Other and further features contemplated 60 by the present invention will become apparent as the description progresses.

In the drawings, Figures 1 and 1^a show circuits and apparatus of a subscriber's line and a first line finder. There is also shown 65 in Fig. 1, a coin collecting device at the substation together with means at the exchange for operating said device. Figs. 2 and 2^a illustrate a second line finder, a group selector and the circuits and apparatus associated 70 therewith. Figs. 3 and 3^a show the circuits and apparatus of a final selector. Figs. 4 and 4^a illustrate the circuits and apparatus of the register and controlling equipment adapted to be associated with the connecting 75 circuit shown in Figs. 2 and 2^a to control the selector switches. Fig. 5 shows a party line with coin collecting devices provided at each substation with means at the exchange individual to the line for controlling the operation of said devices. Figs. 1, 1^a, 2, 2^a, 3, 3^a, 4 and 4^a taken together comprise a dia- 80 grammatic showing of a system involving the principles of this invention.

The figures should be arranged as follows: 85 Figs. 1, 1^a, 2, 2^a, 3 and 3^a placed in order from left to right with Fig. 4 beneath Fig. 2, and Fig. 4^a beneath Fig. 2^a. To include the modification shown in Fig. 5 in the system disclosed, this figure may be substituted 90 for Fig. 1.

The line finders, group selectors and sequence switches are of the type already known in the art and need not be described specifically herein, it being sufficient to describe their relation in the circuits. Also the method of showing the sequence switch contacts and the indication of the operating positions of the sequence switches are well understood and mention need only be made 100 that in Fig. 2 and Fig. 2^a the contacts of the three sequence switches are shown separated from each other by means of dotted lines.

The mechanical construction of the registers and the controlling equipment will be 105 sufficiently understood from the following description thereof:

The final selector switch differs from the usual type of switch only by the addition of two extra notches in the interrupter 110

plate between the first ten notches and the second ten notches. It will be recalled that switches of this character have a capacity of 200 lines and the contacts of these lines are arranged in ten levels of 20 lines each. Between the bank of the 100 lines individual to a given hundred and the bank of 100 lines individual to the second hundred, that is to say, between the first ten lines and the second ten lines of each level, there is a spacing plate. In selectors of this type, it has not been customary to utilize the spacing between the two banks of line contacts, the interrupter plate at the top of the selector being made smooth over the portion thereof corresponding to the space. In the final selector switches disclosed herein, however, two notches are cut in the interrupter plate corresponding to the spacing between the banks for a purpose to be hereinafter described. That is to say, in selecting a line, in the first ten lines on a given level, the interrupter will operate a number of times corresponding to the number of lines passed over, whereas in selecting a line in the second set of ten contacts on such level, the interrupter will operate a number of times corresponding to the number of contacts passed over plus two. For a detailed description of the construction and operation of a final selector switch of this character reference is made to the patent of Polinowsky, No. 1,193,053, issued August 1, 1916. The line finders, group selector, final selector, the controlling sequence switches therefore together with the register controlling equipment disclosed in said patent are in general similar in construction and operation to the apparatus comprising the system in which the present invention is embodied.

It is thought that the invention as disclosed herein will be best understood from a detailed description of the operation of the system shown.

Assuming that the subscriber at the substation indicated at 120 desires to converse with the subscriber at substation 320, whose number, for example is 307, he first inserts a coin 150 in the well-known manner in the slot of the coin collector at the substation and removes his receiver from the switchhook. A circuit is therefore established for line relay 121 from battery through the winding of said relay, back contact and armature of relay 151, left-hand contact of relay 139 over the upper conductor of the line, through the winding of the operating magnet 152, coin 150 to ground. Magnet 152 being marginal does not operate, but the line relay 121 attracts its armature to close a circuit for the common starting relays 122. The relay 121 also closes a circuit from battery through the inner windings of relays 122 to the multiple terminals 132 of all first line finders having access to the group con-

taining the calling line, thereby placing a selectable potential thereon. Relays 122 complete a circuit from ground over their armatures and contacts, sequence switch contacts 104 of all idle first line finders in the group, armature and back contact of relays 137, sequence switch contacts 103 to the power magnets 123 of such line finders, which therefore start in motion moving their brushes 125, 126, 127 and 128 over the terminals 129, 130, 131 and 132 to search for the calling line in the usual way. As soon as one of these finders advances its brush 128 into contact with the terminal 132 of the calling line, a selectable condition will be found thereon and an energizing circuit completed for the right-hand high resistance winding of test relay 135 over sequence switch contact 102 bottom, contact 108 top, to ground either at the interrupter brush 136 or to the winding of relay 137 and sequence switch contact 106 bottom. Relay 135 energizes and closes a circuit for its left-hand low resistance winding in shunt of its right-hand winding. As soon as the brushes are accurately centered and the shunt around the second test relay 137 is removed at the interrupter brush 136, relay 137 energizes in series with the left-hand winding of relay 135 to ground at contact 106 bottom. The low resistance of this circuit so reduces the potential upon terminal 132 that the calling line is rendered non-selectable to other first line finders. Relay 137 by attracting its armature opens the circuit of the power magnet 123 and closes a circuit from ground, armatures and contacts of relays 122, sequence switch contact 104, armature and front contact of relay 137, contact 105 top, winding of the sequence switch magnet 100 to battery and ground and also in parallel therewith a circuit over sequence switch contact 153, winding of the holding magnet 138 to battery and ground. The holding magnet 138 brings the brush carriage to rest with the brushes accurately centered, while sequence switch 100 moves out of position 1 and into position 2. In position 2, ground is placed upon the terminal 132 over sequence switch contact 112 bottom to maintain the calling line busy, the contact 102 having been opened when the sequence switch 100 passed out of position 1. In the second position of contact 110, the cutoff relay 139 is energized causing the deenergization of the line relay 121 and consequently the deenergization of the starting relays 122, provided no other line in the group is calling at this time. Cutoff relay 139 also closes a circuit from battery over its right-hand armature and front contact, right-hand winding of slow-to-release relay 151 to ground which causes said relay to energize. In parallel with the circuit for the cutoff relay 139, a circuit is closed for relay 154, which,

- however, being marginal, does not energize. The deenergization of relay 121 opens the battery circuit to the terminals 132 of the calling line and such line now having been seized and being maintained busy, no selectable potential is possible upon the test terminals thereof. The sequence switch 100 on coming into position 2 establishes a circuit from ground, contact 113, contact 602 bottom of sequence switch 600, armature and back contact of relay 237, contact 603 top, through the winding of the power magnet 226 of the idle second line finders having access to the calling first line finder to battery and ground. The brush carriages of such idle line finders, therefore, move the brushes 227, 228, 229 and 230 over the contacts 231, 232, 233 and 234 of the line appearing in their multiple banks. The sequence switch 100 on coming into its second position places a selectable potential upon the multiple terminals 234 over a circuit extending from battery, resistance 141 contact 108 bottom, winding of relay 137, contact 106 top, contact 107 to the terminals 234. When the brush 230 of one of the second line finders comes in contact with the terminal 234 upon which this selectable potential exists, the test relay 235 of such second line finder is energized in a circuit from battery, as traced to the terminal 234 and thence by way of brush 230, sequence switch contact 604 top, through the right-hand high resistance winding of relay 235, sequence switch contact 605 top, through the winding of the second test relay 237, sequence switch contact 606 top to ground. Relay 235 energizes and closes a circuit for its left-hand low resistance winding in parallel to its right-hand winding, thus reducing the potential upon the terminal 234 to render the connecting circuit busy to other second line finders. The second test relay 237 is short-circuited by a direct path to ground at the interrupter brush 236 and the brush carriage continues to rotate until the brushes are accurately centered at which time such short circuit is removed at the interrupter brush 236. Relay 237 energizes in series with relay 235. The relay 237, by attracting its armature, opens the above traced circuit for the power magnet 226 and closes a circuit for holding magnet 238, thus bringing the brush carriage to rest. At the same time, a circuit for sequence switch 600 is closed in parallel to the circuit for holding magnet 238 and the sequence switch moves into its second position.
- As the sequence switch 600 leaves its first position and until it is passed through its seventh position, a test guard is maintained upon the terminal 234 by the closure of the contact 610, connecting ground to such terminal.
- As the sequence switch 600 was passing

from its first to its second position, the contact 611 was closed sufficiently long to drive sequence switch 200 out of position 1 and into position 2 over a circuit including sequence switch contact 202 bottom and contacts 611 top. 70

In position 2 of sequence switch 600 and in position 2 of sequence switch 200, the selection of an idle register will take place. Before considering this operation, however, 75 the effect of the seizure of the circuit connected to the first line finder and the movement of sequence switch 200 into position 2 will be described. When the test relay 235 was energized, the circuit therefor included 80 the relay 137 at the first line finder. The relay 137 energizes and closes a circuit from battery to the winding of sequence switch magnet 100, contact 105 top, front contact and armature of relay 137 to ground at 85 contact 104 bottom, whereby sequence switch 100 moves from position 2 into position 5. In position 5, the circuit of relay 137 includes the resistance 140, contact 107 having opened on leaving position 4, as well as 90 the resistance 141, but such relay will remain energized until sequence switch contact 610 leaves position 7.

In position 5 of the sequence switch 100, the contact 110 being opened, the circuit 95 for the cutoff relay 139 now includes the contact 102, the relay 135 and the contact 207, sequence switch 200 being at this time in its second position. In this position, the contact 112 is opened and the circuit of the 100 calling line is extended over contacts 210 top and 211 top to the repeating coil 239. As the sequence switch 600 came into its second position, the contacts 604 bottom, 619 top, 605 bottom, 606 bottom, and 613 105 bottom were closed. If, at this time, the sequence switch 700 individual to the connecting circuit shown, is in such position that an idle register is connected by said sequence switch to the leads shown, the relay 240 will be energized in a circuit from ground, sequence switch contact 703, winding of relay 240, contact 619 top, winding of relay 235, contact 604 bottom, contact 704 bottom, winding of relay 426, contact 405 110 of the sequence switch 400 individual to such idle register resistance 490 to battery and ground. If, however, the equipment with which the leads are connected over such sequence switch 700 is already busy, 115 the test circuit including the relay 240 of some other connecting circuit will already be closed through the relay 426 and insufficient current will pass through the relay 240 shown to cause its energization. A circuit will therefore be established from battery through the winding of sequence switch motor magnet 700, contact 702, contact 613 bottom, back contact and armature of relay 240 to ground. Sequence switch 120

125

130

700 thereupon moves out of the position in which it is standing and continues to move until it reaches a position in which the connecting circuit shown is associated with an 5 idle register equipment at which time the relay 240 receives sufficient current in series with relay 426 of such idle equipment to energize. Relay 240 opens the circuit of the sequence switch 700 causing the same 10 to stop and the relay 237 being energized in parallel with relay 240 closes a circuit from battery through the winding of sequence switch motor magnet 600, contact 607 top, front contact and armature of relay 15 237, contact 602 top, back contact and armature of relay 242 to ground to drive sequence switch 600 from its second and into its third position. In this position, relay 240 and relay 237 are directly connected over 20 contacts 619 bottom, and contact 704 bottom, for example as shown, to the starting relay 426. The idle registering equipment is now seized and is inaccessible to any other connecting circuit having access there- 25 to until it has performed its function or has been released by the replacement of the receiver of the calling subscriber.

As the sequence switch 600 moved into its third position, it closed a circuit over its contact 609 including contact 202 top, to drive sequence switch 200 into its third position. In the third position of sequence switch 200, the calling subscriber's line is connected over contacts 211 and 210 bottom to the register 35 controlling equipment ready for the transmission of impulses in accordance with the designation of the called line. The impulse circuit for setting the controlling registers may be traced from battery through the 40 winding of stepping relay 427, contact 402, contact 707, contact 210 bottom, brush 228, terminal 232, brush 126, terminal 130 over the loop of the substation 120 and returning by way of terminal 129, brush 125, terminal 45 231 brush 227 to ground at contact 211 bottom.

The relay 426 being energized as above described, a circuit is closed from ground at its right-hand armature and front contact, 50 over contact 404 bottom to drive the sequence switch 400 out of position 1 and into position 4.

It will be observed that the calling subscriber's supervisory relay 241, which, at this 55 time, controls the restoration and which, in positions 2 and 4 and positions subsequent thereto, is directly under the control of the calling subscriber, is energized by the closure of contact 205 as sequence switch 200 comes 60 into position 3, thus preventing relay 241 from effecting a premature release of the apparatus. The mechanism will now await the sending of impulses by the calling subscriber, such impulses being arranged in groups cor- 65 responding to the complement of the digits

of the numerical designation of the called line, that is to say, the called subscriber's number being assumed to be 307, the calling subscriber will transmit to the central office three series of impulses, the first series comprising seven impulses, the second series comprising ten impulses, and the third series comprising three impulses. In each of these series of impulses, the last impulse sent will be relatively longer than the other impulses 70 of the series. The sender by which these impulses are sent may be of any desired construction provided that the impulses are sent in the complementary manner and that the last impulse of each group is comparatively 75 longer.

The system herein disclosed is, for convenience, shown as a 1000 line system. In such a system there will be five groups of final selectors each accessible to 200 lines 80 thereof, and the group selectors used will have only five of the ten banks utilized, one bank of contacts being connected to the trunk lines of the group of final selectors individual to one group of 200 lines, another 85 connected to another group of final selectors individual to another group of 200 lines and so on. In accordance with the translating system disclosed herein, the selection in the group selected, when the trunk line leading 90 to the group of lines having the proper hundreds digit is such that if the hundreds digit of the desired line is 0 or 1, the tripping spindle of the group selector will be adjusted to release the proper set of brushes 95 on the brush carriage by the movement of such spindle one step. If the hundreds digit of the desired line is 2 or 3, the tripping spindle will be moved three steps. If the hundreds digit is 4 or 5, the tripping spindle 100 will be moved five steps and so on. It will be understood that if the system comprises more than 1000 lines, the intermediate stages on the group selectors that is, the second, fourth, sixth, eighth and tenth will be reserved for 105 use when a trunk line is desired leading to the groups of final selectors having access to lines in the second thousand. It will be further understood that by properly rearranging the tripping teeth on the spindle, the five 110 levels and terminals which are used, may be arranged, if desired, adjacently to each other so that the first level will be selected by a single step of the tripping spindle, the second level by three steps of such spindle, the third level by five steps of such spindle and so on. Furthermore, any other preferred or desired method of grouping the lines may be used.

The operation, therefore, of the subscriber's sending mechanism to send the hundreds digit, three steps will produce seven breaks in the circuit traced including the stepping relay 427, the last of such breaks being relatively longer than the others. Upon the en- 125 130

- ergization of the stepping relay 427, a circuit was closed from ground over its armature and front contact, contact and right-hand armature of relay 428, sequence switch 5 contact 408 through the lower winding of the hundreds register 429 to battery and ground. This causes the energization of the power magnet of such register which moves only midway between its 0 and its first position. 10 At this time, a circuit is closed from battery through the upper winding of register 429, contact 471 to ground at the right-hand armature and front contact of relay 426. 15 The two windings of the register are arranged in differential relation to each other, such that when both are energized, the register will not move, whereas when a circuit is closed through but one of such windings, 20 the register is operated. The register 429 having, therefore, been brought to rest between its 0 and its first position will await the opening of the circuit through its lower winding at the front contact of stepping 25 relay 427. Therefore, as the result of the first interruption in the circuit by the operation of the subscriber's sender and the consequent deenergization of the stepping relay 427, the hundreds register will move into its 30 first position, the circuit for the upper winding thereof being also open as soon as the first position is reached by the local contact 471, whereupon the register stops in position 1. Upon the cessation of the first interruption, 35 the relay 427 is again energized and register 429 is driven to a position intermediate of its first and second positions and correspondingly in response to the second interruption, it will be driven into its second 40 position. Therefore, as the circuit is interrupted seven times upon the cessation of the seventh interruption, the register 429 will be driven into its seventh position. As this interruption is a longer one, the stepping 45 relay 427 will be deenergized sufficiently long for the armature to close at its back contact, a circuit for the slow energizing relay 428, including sequence switch contact 413. Relay 428 being slow to act 50 did not energize during the short-closures of its circuit at the back contact and armature of relay 427. The relay 428 opens the circuit of the register 429 at its right-hand armature, in order to prevent a false operation 55 of such register and closes at its left-hand armature, a circuit including the contact 404 top to drive the sequence switch 400 out of position 4 and into position 6. The hundreds register has now been set and 60 it may proceed to control selection in the group selector. For this purpose, the outgoing sequence switch 450 shown to the right of Fig. 4^a has been started by the closure of contact 407 bottom, as the incoming 65 sequence switch 400 passed through its fifth
- position. Sequence switch 450 moves into its fourth position. Before, however, describing the selection operation initiated by the movement of the outgoing sequence switch 450 further registering operations 70 will be described.
- Upon the reestablishment of the transmitting circuit and the consequent energization of the stepping relay 427, the circuit through the lower winding of the tens register 430 is closed in the sixth position of sequence switch 400 over contact 409 top. In response to the group of interruptions now being produced at the substation comprising ten interruptions, the tens register is caused 75 to move into its tenth position in a manner precisely the same as that described in connection with the hundreds register. The last interruption of this group being relatively longer, the change-over relay 428 energizes and closes a circuit over sequence switch contact 404 top to drive sequence switch 400 into position 8 to place the units register under the control of the stepping relay. 80 The closure of the controlling circuit including stepping relay 427 and its interruption three times to send the complement of the digit 7, will cause the units register 431 to move into its third position 85 in the manner now well understood, and the final interruption being comparatively longer, relay 428 energizes and closes a circuit for driving sequence switch 400 out of position 8 and into position 9. The incoming sequence switch 400 will remain in its 90 ninth position until, at the conclusion of the selection controlling operation, it is started in motion by a circuit closed by the outgoing sequence switch 450 returning to its normal position which will hereinafter be described. 95
- The registers have now been set to properly control the selection in accordance with the numerical designation of the desired subscriber's line, the hundreds register having been moved to its seventh position, the tens register to its tenth position and the units register to its third position. As the incoming sequence switch 400 reached its 100 ninth position, a circuit was closed over contact 412 and contact 206 bottom to drive the sequence switch 200 out of its third and into its fourth position, in which position the supervisory relay 241 is again placed under the control of the calling subscriber and the 110 impulse sending circuit is disconnected from the registers at the contacts 210 and 211 bottom. 115
- The outgoing sequence switch 450 in passing from its first to its second positions, 120 makes a test of the hundreds register to determine whether or not such register is set for an even or an odd digit. This testing circuit is traceable from battery through the winding of the translating relay 432, con- 125
- 130

tact 459 of sequence switch 450 closed in position 1½, contact 474 of the hundreds register 429. It having been found to be odd, the hundreds register being in its seventh position and the contact 474 consequently being closed, the translating relay 432 is energized. It will be observed that the contact 474 of the hundreds register is closed in the following positions, only a few of which, 10 for convenience, are indicated upon the drawings:

15	$\frac{1}{2}$ to 1 $\frac{2}{2}$ to 3 $\frac{4}{2}$ to 5 $\frac{6}{2}$ to 7 $\frac{8}{2}$ to 9 $10\frac{1}{2}$ to 11

The relay 432 on energizing closes a locking circuit over its right-hand armature and 20 sequence switch contact 455, such relay remaining energized until the sequence switch 450 leaves its ninth position. As the sequence switch 450 passes through its second position, the closure and the subsequent 25 opening of the circuit of the lower winding of the hundreds register 429 at sequence switch contact 458 bottom causes said register to take an additional step, that is, in this case, to be moved into its eighth position. 30 Also, as sequence switch 450 passes through its third position, the translating relay 432 being locked up, a circuit is established over the contact 460 top, left-hand armature of such relay and contact 461 bottom to drive 35 the hundreds register 429 another step from its eighth to its ninth position.

The sequence switch 600 being already in its third position, the fundamental circuit from the registering and controlling 40 equipment is closed to the group selector shown on Fig. 2^a. This circuit may be traced from battery through the winding of relay 242, contact 612, contact 473 of the hundreds register 429, contact 457, winding 5 of the stepping relay 433 to ground at contact 611. The energization of relay 242 closes a circuit from ground over its armature and front contact, sequence switch contact 614, for the sequence switch 600, which 50 thereupon moves from position 3 into position 4. In position 4 of sequence switch 600, a circuit is closed for the tripping spindle, power magnet 243 which includes the front contact and armature of relay 242. As the 55 relay 433 was energized coincidentally with the energization of the line relay 242, it closed a circuit over sequence switch contact 458 top for the lower winding of the hundreds register 429. The register therefore, 60 moved a half of a position, that is, until the closure of the local contact 471 completed a circuit for the upper winding of the register. As the tripping spindle of the group selector begins to rotate, it intermittently 65 closes a circuit to ground for the line relay

242 in shunt of the stepping relay 433. Upon the first closure of this shunt circuit, relay 433 deenergizes and opening the circuit of the lower winding of the hundreds register permits such register to advance 70 into its tenth position. From this position, it will be moved intermediate of its tenth and eleventh positions when relay 433 is again energized as the tripping spindle comes into its set position to trip the first set 75 of brushes of the group selector and in the continued motion of the tripping spindle a second deenergization of relay 433 takes place and the hundreds register is moved into its eleventh position. The register advances in this manner one position for each 80 stage through which the tripping spindle passes until it reaches its 0 or normal position. In the 0 position of the hundreds register, the contact 473 is opened and not only 85 will the stepping relay 433 remain deenergized when connection to ground is broken by the tripping spindle, but also the line relay 242 will deenergize, since both the fundamental circuit and the branch circuit therefor 90 to ground at the tripping spindle interrupter contact are opened. Relay 242 deenergizing, opens the circuit for the power magnet 243 bringing the tripping spindle to rest in position to select the desired set of brushes. 95 Such tripping spindle having moved three steps is in position to release the third set of brushes on the brush carriage, as it will be recalled that a trunk leading to the group of final selectors in which the desired line 100 appears is to be found in the third level of such group selector.

As the hundreds register reached its normal position, if the incoming sequence switch 400 is in its ninth position, that is, 105 if tens and units registration is completed, a circuit will be closed from battery through the winding of the outgoing sequence switch magnet 450, contact 456, contact 472, contact 410 to ground to drive sequence 110 switch 450 into its sixth position, in which it is ready to control tens selection as soon as an idle trunk line to the proper final selector has been found and seized by the group selector as will be described. If the 115 incoming sequence switch 400 has not reached its ninth position, the outgoing sequence switch 450 will remain in its fourth position moving to its sixth position as soon as sequence switch 400 reaches its ninth position. 120

When relay 242 released its armature, a circuit was closed from battery through the winding of sequence switch magnet 600, contact 607 bottom, back contact and armature 125 of relay 237, contact 602 top to ground at the back contact and armature of relay 242 to drive sequence switch 600 into its fifth position. In this position, a circuit is closed for the group selector power magnet 244 130

from battery through the winding of such magnet, sequence switch contact 603 bottom, back contact and armature of relay 237, contact 602 top, to ground at the armature of relay 242. The brush carriage of the group selector begins to rotate, releases the selector set of brushes and moves them over the terminals of trunk lines of the level to which they have access in search of 5 an idle one thereof. So long as the test brush 247 makes contact with the test terminals of trunk lines which are busy, insufficient potential will be found thereon to cause the energization of the test relay 235, 10 due to the fact that the low resistance winding of a test relay corresponding to the relay 235 of some other group selector is already connected to the test terminal. As soon, however, as the brushes come in contact 15 with a set of terminals of an idle trunk line, full potential will be found thereon and a circuit is established from battery at the final selector over sequence switch contact 312 bottom, contact 314 top, through 20 the left-hand winding of relay 331 over the test conductor, test brush 247 of the group selector, right-hand high resistance winding of test relay 235, contact 605 top, through the winding of the second test relay 237, 25 contact 606 top to ground. Relay 235 energizes, but relay 237 being shunted by a direct path to ground at the interrupter brush 269 of the group selector does not energize until the brushes are accurately centered upon the 30 terminals of the selected trunk. Relay 235, by attracting its armature, closes a circuit through its left-hand low resistance winding in shunt of its high resistance winding, which thereby reduces the potential upon 35 test terminal of the trunk line to render the same non-selectable to other switches. As soon as the brush carriage has properly centered the brushes upon the terminals of the trunk, the relay 237 energizes and opens the 40 above traced circuit for the power magnet 244 to bring the brush carriage to rest. The operation of the relay 237 closes a circuit for the holding magnet 250 to insure the accurate centering of the brushes on the 45 terminals of the trunk. This circuit may be traced from battery through the winding of said holding magnet, contact 608 top, contact 607 top, front contact and armature of relay 237, contact 602 top, to ground 50 at the back contact and armature of relay 242. Relay 237 also closes a circuit for the sequence switch 600 traceable from battery through the winding of the power magnet of such sequence switch, contact 607 top, 55 front contact and armature of relay 237, contact 602 top to ground at the armature of relay 242. The sequence switch 600 moves from its fifth into its sixth position. In this position of the sequence switch 600, 60 the fundamental circuit is closed from the registers over sequence switch contacts 616 and 617 to the final selector, provided the outgoing sequence switch has reached its sixth position. When the sequence switch 450 was driven out of its fourth position 70 upon the completion of the hundreds selection operation, it moved directly into its sixth position, but in passing through its fifth position it closed a momentary circuit at contact 462 bottom for the lower winding 75 of the tens register 430 to drive such register from its tenth into its eleventh position. When the fundamental circuit is closed in the sixth position of sequence switch 450 both relays 332 at the final selector and 433 80 at the register equipment are energized. The fundamental circuit may be traced from battery through the winding of the line relay 332, contact 308 top, group selector brush 246, contact 617 bottom, contact 483 85 of the tens register, contact 453 top through the winding of stepping relay 433, contact 616 bottom, group selector brush 245 to ground at contact 309 top of the final selector sequence switch 300. The energization 90 of relay 332 closed a circuit over sequence switch contact 303 top to drive sequence switch 300 into position 2. In position 2 of sequence switch 300, a circuit is closed for the tripping spindle power magnet 333 over contact 302 bottom, to ground at the front contact and armature of the line relay 332. The brush tripping spindle begins to rotate in a well-known manner and as it passes through each brush tripping position, the interrupter contact is closed to complete a momentary circuit for the line relay 332 in shunt of the stepping relay 433 at the register equipment. For each deenergization of the stepping relay 433 the tens 95 register is advanced a half position where it is subsequently moved to the full position in the manner above described. 100

It will be recalled that the tens digit of the desired line is 0 and therefore such line 110 is to be found in the first level of the final selector. It will therefore be necessary that the selecting operation of the final selector terminates when the tripping spindle is moved one step and is in position to release 115 the set of brushes corresponding to the first level of contacts. It will also be recalled that the tens register was set by the subscriber in its tenth position and subsequently moved to its eleventh position when sequence switch 450 passed through position 5. When, therefore, the tripping spindle at the final selector moves its first step the shunting of the relay 433 drives the tens register into its normal position. This 120 movement of the tens register immediately opens the fundamental circuit at the spring 483 so that when the shunt circuit at the tripping spindle interrupter is opened both relay 433 and relay 332 are deenergized. At 125 130

the same time the closure of the contacts 482 of the tens register completes a circuit from ground, contact 411, contact 482, contact 463 top, through the winding of the outgoing sequence switch magnet 450 to battery to drive such sequence switch into its eighth position where it is ready to control the units selection. Upon the de-energization of the line relay 332 of the final selector, the tripping 5 spindle is stopped and a circuit is closed from ground, armature and back contact of relay 332, sequence switch contact 303 bottom, through the winding of sequence switch magnet 300 to battery and this sequence 10 switch moves from its second to its fourth position. As the outgoing sequence switch 450 passes through its seventh position, a momentary circuit for the lower winding of the units register 431 is closed at the contact 15 454 bottom to drive the units register an additional step or into its fourth position. The closure at this time of the fundamental circuit again energizes relays 332 and 433, but this time in the eighth position of sequence switch 300. In the fourth position 20 of the sequence switch 300 a circuit is closed for the brush carriage power magnet 345 of the final selector including the contact 306 top and the front contact and armature 25 of relay 332. In the initial movement of the brush carriage the proper set of brushes is tripped and in the continued movement thereof, such brushes are trailed over the sets of terminals individual to the lines appearing in this level of contacts. For each 30 movement of the brushes to a set of terminals, the interrupter 337 closes in the well-known manner, a circuit to ground for the line relay 332 in shunt of the stepping 35 relay 433. The intermittent de-energization of relay 433 due to the shunting action of the interrupter 337 at the final selector causes the units register to be stepped through its successive positions. At the end 40 of eight such operations of the relay 433, the units register will be brought into its 0 or normal position, the selected brushes of the final selector at this time being about to make contact with the eighth or No. 7 set of 45 contacts of the level to which they are individual. It will be recalled, however, that since the desired line is located in an odd hundred, such line is to be found in the second half of the final selector bank and it 50 is therefore necessary that the selecting operation should not terminate at this time. For this reason the fundamental circuit is not opened at the contact 493, as the register 431 reaches its normal position since a shunt 55 is maintained around such contact at the left-hand armature and contact of the translating relay 432. This shunt circuit may be traced around the contact 493 of the units register 431 over contact 460 bottom, left-hand armature of relay 432, contact 461 top, 60 contact 453 bottom and thence through the stepping relay 433 as hereinbefore described. It will be recalled that the translating relay 432 was locked up when the sequence switch 450 passed from position 1 to position 2, 70 since the hundreds register 429 was found in a position corresponding to an odd hundred. The fundamental circuit not being open at this time, the brush carriage on the final selector continues to move until the 75 units register 431 has made a complete revolution. This means that the units register will take 12 additional steps. As has been hereinbefore mentioned, the interrupter segment of the final selector is provided with 80 two additional notches located between the first and second groups. In the case as is herein being described that the desired line is located in the second group, at the final selector it is necessary that the units register 85 should be driven through a complete cycle after having been restored to normal before it can open the fundamental circuit and since, such register is provided with twelve positions, it becomes necessary to arrange 90 for two additional steps. For this purpose, the extra notches are provided in the interrupter plate. This arrangement is clearly shown and described in the above mentioned 95 patent to Polinkowsky No. 1,193,053. 95

As the units register 431 passed through its normal position the first time without stopping, a circuit was closed from battery through the winding of the sequence switch magnet 450, contact 463 bottom, contact 492 100 to ground. The outgoing sequence switch 450 thereupon moved from its eighth to its tenth position. On leaving its ninth position, the locking circuit for the translating relay 432 is opened permitting said relay to 105 de-energize and also the sequence switch contacts 460 bottom and 461 top are opened. Therefore, when the units register reaches its normal position, the above traced shunt around the contact 493 which previously 110 maintained the fundamental circuit closed, is now opened and consequently the stepping relay 433 is de-energized and also the line relay 332 of the final selector as soon as the brushes are accurately centered upon the 115 terminals of the desired line. The units register 431 on reaching its normal position, closes a circuit including its contact 492 and sequence switch contact 463 to drive the outgoing sequence switch from position 10 to 120 position 1. As the sequence switch 450 passes through the position 11, a circuit is closed including sequence switch contact 455 bottom and contact 407 top to drive the incoming sequence switch 400 into its normal 125 position. The desired line having now been selected, the register equipment being no longer required for this connection the sequence switch 400 on leaving its ninth position opens the circuit of the relays 426 and 130

240 at the contact 406, which circuit had been substituted for the one originally established over the contact 405. Relays 426 and 240 are deenergized. The deenergization of relay 426 and the restoration of the sequence switch 400 to normal will cause the registering equipment shown on Fig. 4 to test idle and accessible to any connecting circuit taken for use which has access to the 10 same. At the same time that relay 426 is deenergized, relay 240 also deenergizes and closes a circuit including the sequence switch contact 613 to drive the sequence switch 600 out of its sixth position and into its seventh 15 position, which is the talking position for this sequence switch. As sequence switch 600 passes from position 6 to 7, a momentary circuit is closed at contact 611 top which also includes contact 202 bottom to drive 20 the sequence switch 200 out of position 4 and into position 5. The sequence switches 200 and 600 remain in these positions awaiting further operations of the final selector mechanism.

25 Upon the deenergization of the relay 332, a circuit is closed including sequence switch contact 303 bottom to drive sequence switch 300 out of position 4 and into position 6. When the trunk line to the final selector was 30 first seized, it will be recalled that the seizing circuit included the left-hand winding of the relay 331, and contact 314 top. This relay was, therefore, energized and closed for itself a circuit to take the place of the 35 original energizing circuit through the contact 312 bottom which original circuit is opened as soon as sequence switch 300 leaves position 1. This substitute circuit for relay 331 includes its right-hand armature and 40 sequence switch contact 314 top. As soon as sequence switch 300 moves from its fourth to its fifth position, the contact 314 top is opened and 314 bottom is closed. Relay 331 is maintained energized, both of its 45 windings being now included in the circuit and battery is connected over the contact 314 bottom through the test relay 339. At the same time, the contact 307 top is closed, connecting battery with the high re- 50 sistance right-hand winding of test relay 349. The fifth position of sequence switch 300 is the testing position thereof. If, in this position full potential is found on the test terminal 342 of the called line indicating that the line is idle, the test relay 349 energizes. If, on the other hand, the normal potential upon such test terminal 342 is reduced by such line being busy, either as 55 a calling line or as a called line, the test relay 349 does not energize. Assuming first that the line is idle and the test relay 349 consequently energized, it closes a circuit from battery, right-hand armature and contact of relay 331, contact 314 bottom through 60 the winding of relay 339, left-hand low re-

sistance winding of relay 349 to the test terminal 342 of the called line. The resistance of this circuit which is in parallel to the circuit including the right-hand high resistance winding of the test relay 349 is sufficiently low to cause a reduction of the potential on the test terminal 342, thus rendering the called line busy to other selectors. Relay 339 also energizes and as soon as sequence switch 300 reaches its sixth position, 70 it will find a circuit closed over contact 305 bottom, front contact and armature of relay 339 to ground at the back contact and armature of relay 332. Sequence switch 300 therefore moves into position 10. A second 80 circuit is also closed at the contact 317 to drive sequence switch 300 off position six and into position ten. The sixth position of this sequence switch is provided for hunting an idle line to a private branch exchange in case the particular line selected is found busy. The apparatus for performing this operation is not shown, however, and in order to drive the sequence switch through its sixth position, which is, as 85 shown, an idle position where the desired line is found idle or busy, the contact 317 is provided.

On reaching position 10, sequence switch 300 immediately passes to position 12, by 90 means of the above traced circuit which is closed at the contact 305 in positions 10 and 11.

The 12th position of the sequence switch 300 is the ringing position. Current from 100 the ringing source is projected over the called line in a circuit including the ringing relay 343 and sequence switch contacts 310 and 311 closed in position 12.

As sequence switch 300 passed through 105 position 8, the trunk line leading from the group selector to the final selector was bridged by the closure of the sequence switch contact 309. This causes a momentary energization of the called line supervisory relay 248 in a circuit including battery and the right-hand windings of the repeating coil 239. Supervisory relay 248 by attracting its armature, closes a circuit from ground, armature and front contact 110 of said relay, contact 206 top, through the winding of the sequence switch magnet 200 to battery to drive such sequence switch out of position 5 and into position 8. In position 8, the calling subscriber would receive 115 a busy tone by reason of the fact that the secondary winding of the busy tone machine is bridged across the line by the closure of sequence switch contacts 212 and 213, were it not that almost immediately thereafter 120 the sequence switch 300 passes through position 11½ causing a secondary momentary energization of the called line supervisory relay 248. Relay 248, in energizing, a second time closes a circuit as above described 125 130

over sequence switch contact 206 to drive sequence switch 200 into position 11. In this position of sequence switch 200, the secondary winding of the ringing tone machine is bridged across the line at contacts 212 and 213 and the calling subscriber is notified by a distinct tone that ringing current is being placed upon the called line. As soon as the called subscriber answers, the 10 resistance in series with the ringing relay 343 is sufficiently reduced to permit the energization thereof in the well-known manner and which, on attracting its armature, closes a circuit over the sequence switch contact 305 top to drive the sequence switch 300 into position 13. In position 13, the talking circuit is completed from the repeating coil 239 through to the called line by means of the contacts 310 and 311. Relay 15 248 is therefore again energized and closes 20 a circuit as above described including the contact 206 to drive sequence switch 200 out of position 11 and into position 14. The sequence switch 100 being in its fifth position, the sequence 200 being in its fourteenth position, the sequence switch 600 being in its seventh position and the sequence switch 300 being in its thirteenth position, the calling subscriber and the called subscriber are 30 now connected for conversation, talking battery being supplied over the windings of the repeating coil 239.

The operation described is the normal operation of the system in which an idle line 35 is selected, seized and signaled and the called subscriber responds. In such an operation it will be observed that the called line supervisory relay 248 is energized three times, first to move the sequence switch 200 from position 5 to position 8, then from position 8 to position 11 and finally from position 11 to position 14. The effect of these operations will appear hereinafter. Disconnection may take place under the 40 control of either subscriber. The call having been successful the call should be charged to the calling subscriber, whether both subscribers restore their receivers to the hook or only one of them does so regardless of whether such subscriber is the calling or the called subscriber. If the calling subscriber should be the first to replace his receiver, the deenergization of relay 241 closes a circuit from ground, contact 352 45 top, contact and armature of relay 241, contact 209 bottom through the winding of sequence switch magnet 600 to drive such sequence switch from its seventh to its eighteenth position. Similarly the restoration 50 of the called subscriber's receiver to the switchhook causes the deenergization of relay 248 which closes a circuit from ground, armature and contact of said relay, contact 203, contact 209 bottom to drive sequence 55 switch 600 from position 7 to position 18.

The restoration therefore of the receiver of either party causes the movement of sequence switch 600 to its eighteenth position. As sequence switch 600 moved out of position 7, it opened at contact 610 top, the 70 above traced circuit for the relay 137 at the first line finder switch. Relay 137, by retracting its armature, closes a circuit from ground, contact 104 bottom, armature and back contact of relay 137, contact 105 bottom to the winding of the sequence switch magnet 100 to battery and ground to drive such sequence switch out of position 5 and into position 9. As sequence switch 600 moved into position 8, it closed a circuit 75 from battery, through the winding of the magnet of sequence switch 200, contact 202 top to ground at the contact 609 to drive sequence switch 200 out of position 14 and into its normal position. It will be observed 80 that the sequence switches 600, 200 and 100 are simultaneously moving, the sequence switch 600 having started from its seventh position, the sequence switch 100 having started from its fifth position and the sequence switch 200 having started from its fourteenth position. Therefore as the sequence switch 200 is passing through its fifteenth, sixteenth and seventeenth positions, the sequence switch 100, during a part of 85 this time will not have reached its eighth position. Hence, a circuit is closed from the high potential battery 298, sequence switch contact 207 closed from positions 15 to 17, brush 229, terminal 233, right-hand 90 winding of relay 135, contact 102, closed from positions 2 to 7, brush 127, contact 131, through the winding of the marginal relay 154 to ground. This increased battery potential causes the energization of relay 154 which in turn closes a circuit from the positive pole of battery, contact and armature of said relay, left-hand armature and front contact of cutoff relay 139 over the upper conductor of the calling line 100 through the winding of the polarized magnet 152 through the coin 150 to ground. Current of this polarity flowing through the magnet 152 causes the same to operate its armature in such a manner as to collect the 105 coin which, at the same time, opens the circuit just traced to cause the deenergization of the magnet 152. The calling subscriber is thus charged for having completed a successful connection to the called line. 110

On coming into its eighteenth position, sequence switch 600 established the usual restoring circuit for the brush carriage of the group selector which may be traced from battery to the winding of power magnet 125 244, contact 603 bottom, back contact and armature of relay 237, contact 602 top, to ground at the armature of relay 242. The brush carriage rotates and upon reaching its normal or home position, a circuit is 130

closed from battery, contact 618, brush 269 in its home position, winding of relay 237, contact 606 top to ground. Relay 237, by energizing, stops the movement of the 5 brush carriage in the usual manner and also closes a circuit from ground, armature and back contact of relay 242, contact 602 top, armature and front contact of relay 237, contact 607 top through the winding of sequence switch magnet 600 to battery to drive said sequence switch out of position 10 18 and into its normal position 1.

If the calling subscriber has not replaced his receiver on the hook, the sequence switch 15 100 in passing into its eighth position, as above described again closes a circuit for relay 137 which energizes and opens the circuit, which started sequence switch 100 out of position 5 so that said sequence switch 20 will stop in position 9, since it would otherwise continue to move by reason of the fact that contacts 104 and 105 are closed in this position. The circuit for the energization of relay 137 may be traced from battery, 25 over the contact 108 bottom, through the winding of relay 137, contact 111 closed in position 8, over the lower side of the line, through the loop at the substation 120 and returning over the upper side of the line to 30 ground at contact 112 closed in position 8. As soon, however, as the calling subscriber replaces his receiver to the switchhook, this circuit is opened and relay 137 by retracting its armature closes the above traced circuit 35 to drive sequence switch 100 out of position 9 and into position 1. It will be observed that the cutoff relay 139 is maintained energized in the seventh position of sequence switch 100 in a circuit including contact 102 40 top, and in positions 8 and 9 in a circuit including resistance 199 and sequence switch contact 110 bottom. This control of the cutoff relay is transferred to the first line finder prior to the time that the original energizing circuit for said relay is opened by sequence switch contact 207 at the second line finder leaving its position 17 to insure the maintenance of the energization of said 45 relay.

50 As the sequence switch 600 left its seventh position, it opened at the contacts 605 and 606, a circuit for the relay 331 at the final selector. This relay, therefore, deenergized and closes a circuit from ground over its 55 left-hand armature, contact 308 bottom through the winding of relay 332 to battery and ground. Relay 332 closes a circuit from ground over its armature and front contact, sequence switch contact 303 through the 60 winding of magnet 300 to battery and ground whereupon said sequence switch moves from position 13 into position 16. On reaching position 16, the line circuit being open at the called subscriber's substation, relay 332 deenergizes and closes a cir-

cuit from ground over its armature and back contact, sequence switch contact 303 bottom to drive sequence switch 300 into its eighteenth position. In this position of sequence switch 300, the usual circuits are established 70 to restore the brush carriage of the final selector to its normal position. As the brush carriage reaches its home position, the interrupter brush 337 closes a circuit from ground, sequence switch contact 313 bottom 75 through the winding of relay 332 to battery thus causing said relay to again energize. The relay 332, by attracting its armature, closes a circuit including sequence switch contact 303 top to drive sequence switch 300 80 into its normal position. The entire apparatus is now restored. It will be observed that although the relay 331 at the final selector is deenergized, as soon as sequence switch 600 leaves its seventh position, it is 85 not again energized by the closure of the contact 610 bottom, as such relay 331 controls through its right-hand armature, its cord energizing circuit in all positions except position 1, of the sequence switch 300. 90 In position 8 to 17, a busy condition is maintained on the terminal of the trunk line leading to the final selector by the closure of the contact 610 bottom. At the final selector, when the sequence switch 300 comes into its 95 fifteenth and sixteenth positions, if the called subscriber has not yet restored his receiver to the switchhook, a circuit will be established for the relay 332 traceable from battery through the winding of said relay, 100 contact 308 top, contact 310, brush 335, terminal 341 over the loop of the called line and returning by way of terminal 340, brush 334, contact 311 top to ground at contact 309 top. Therefore, when sequence switch 300 105 reaches position 16, it will remain there, since the above traced circuit for driving it out of position 16, is now opened at the armature of the relay 332, which is energized, due to the fact that the called subscriber has not replaced his receiver to the switchhook. When the called subscriber hangs up his receiver, the relay 332 deenergizes and closes a circuit as described to 110 drive sequence switch 300 out of position 16 115 and into position 18.

It will now be assumed that the called line is busy at the time that it is attempted to establish a connection therewith. The group and final selectors having been selectably controlled by the register controlling equipment in the manner already described to extend the calling line and the brushes 120 334, 335 and 336 of the final selector having been set on the terminal 340, 341, 342 of the 125 called line, which, in this case, is assumed to be busy, as sequence switch 300 passes through its fifth and sixth positions, insufficient potential will be found on the terminal 342 to cause the energization of the 130

test relay 349 over the test circuit including contact 307 top. Consequently no energization of relay 339 takes place and when sequence switch 300 reaches position 10, it 5 will stop and the brush carriage will be restored by means of a circuit closed for the power magnet 345 over sequence switch contact 306 bottom, back contact and armature of relay 339, back contact and armature of 10 relay 332 to ground. It will be seen that as sequence switch 300 has stopped in position 10, only one closure of the trunk line between the group and final selectors is produced at the sequence switch contact 309 15 bottom, namely, as sequence switch 300 passes through position 8. This results in but a single energization of relay 248 and therefore the sequence switch 200 passes only to position 8 where it remains. The busy 20 tone is now placed upon the calling line for a prolonged period, due to the closure of contacts 212 and 213. The calling subscriber, hearing the characteristic tone, is informed that the desired line is busy and 25 initiates restoration by replacing his receiver on the switchhook. As explained, the sequence switch 100 at the first line finder is, at this point, of the operation, standing in position 5, the sequence switch 600 in 30 position 7, while the sequence switch 200 stands in position 8. The replacement of the calling subscriber's receiver to the switchhook causes the deenergization of the calling supervisory relay 241 which 35 completes a circuit including contacts 252 top and 209 top to drive sequence 200 out of position 8. Almost immediately when the sequence switch 200 begins to move as a result of the closure of the circuit referred 40 to, the contact 209 top is opened and contact 209 bottom is closed so that a circuit is now completed for sequence switch 600 which moves out of its seventh position. Restoration now takes place in the first line 45 finder, the second line finder and the group selector precisely as in the normal operation, the sequence switches 100, 200 and 600 being simultaneously in motion. However, it is to be noted that these sequence switches 50 have started from different relative positions, that is to say, while sequence switch 100 has started from position 5 as before and sequence switch 600 has started from position 7, the sequence switch 200 has started 55 in motion from position 8 instead of from position 14, as was the case, after a successful connection. It will be apparent, therefore, that before the sequence switch 200 can reach position 15 to close the above 60 described circuit for the high potential battery 298 at sequence switch contact 207 bottom, the sequence switch 100 will have passed out of position 7 to open such circuit. Therefore, the marginal relay 154 re- 65 mains deenergized. As soon then as se-

quence switch 100 leaves position 9, the holding circuit of the cut-off relay 139 opened at sequence switch contact 110 permits this relay to release its armatures. The closure of the left-hand normal contact of relay 139 establishes a circuit from the negative pole of battery through the left-hand winding of the slow-to-release relay 151, front contact and armature of such relay, normal contact of the relay 139 over 70 the upper side of the calling line through the winding of the polarized magnet 152, coin 150 to ground. The relay 151 which, up to this time has been maintained energized, in a circuit including the right-hand 75 armature and front contact of relay 139 being slow to release, maintains its armature attracted for a period of time after the cut-off relay 139 deenergizes sufficient to permit the operation of the polarized magnet 152 80 at the calling substation. This magnet being energized by current of a polarity opposite to that impressed upon the line after a successful call now operates its armature in such a manner as to restore the coin. 85 The restoration of the coin 150 opens the operating circuit of magnet 152 which restores to its normal position. Relay 151, after an interval, also releases its armature and the apparatus is now in readiness for 90 the initiation of a further call.

The case will now be considered in which a connection is extended to the called line but the called subscriber fails to answer, it being necessary in this instance that no 100 charge be made against the calling subscriber. Where the desired line is idle, the sequence switch 300 moves directly into its twelfth position, as has been before described. During such movement, sequence 105 switch 600 is in its seventh position and the contact 309 having been closed twice, the called supervisory relay 248 receives two momentary energizations and as a result, the sequence switch 200 moves first from position 5 to position 8 and then from position 8 to position 11 where it now stands. At this time, the calling subscriber hears the ringing tone and knows that the called line is being signaled. If the called subscriber does not respond within a reasonable time, the calling subscriber replaces his receiver on the switchhook, thus causing the deenergization of the calling supervisory 110 relay 241, which closes the circuit already described to drive sequence switch 600 out of position 7 and into position 18. This movement of such sequence switch initiates the movement of sequence switches 100 and 200 precisely as during the release of a 115 successfully established connection. In this case, however, the sequence switch 200 starts in a motion from position 11 instead of from position 14. Therefore, before sequence switch 200 can reach its fifteenth 120

130

position in which contact 207 bottom is caused to close the circuit to apply high potential source 298 to operate marginal relay 154, the sequence switch 100 at the first 5 line finder will have passed out of position 7, thereby opening such circuit at the sequence switch contact 102 top. The marginal relay 154 remains inoperative and upon the deenergization of the cut off relay 139, 10 negative pole of battery is applied to the calling subscriber's line as described to operate polarized magnet 152 to restore the coin.

Referring to Fig. 5 of the drawings, the 15 invention is shown as embodied in a system involving party lines. This figure illustrates a party line having four subscribers' substations thereon, each provided with a toll device, such as the coin collectors 700, 701, 20 702 and 703. These coin collectors comprise a polarized operating magnet similar in all respects to the polarized magnet 152 shown in Fig. 1 which are connected at the several substations to the same side of the party 25 line. The apparatus at the exchange associated with the line by means of which the toll devices are operated at the return of an established connection either to collect or refund the coin depending upon the success of 30 the call, is substantially the same as has been already described in connection with the embodiment disclosed in Fig. 1, and therefore, need only be briefly mentioned. Assume that the subscriber at one of the substations, 35 such as substation 704 on the party line desires to extend a telephone connection to some other line, he deposits a coin 705 and removes his receiver from the switchhook. A circuit is thereupon closed for the line re-

40 lay 706 from battery through the winding of said relay, back contact and armature of slow-to-release relay 707, normal left-hand contact of cutoff relay 708 over the upper side of the line through the winding of the 45 polarized operating magnet 700 at the calling substation, coin 705 to ground. The current in this circuit is not sufficient to operate the magnet 700, but the relay 706 attracts its armature. The energization of the 50 line relay 706 causes, in the well-known manner, the operation of the common starting relays 708 which in turn serve to start in operation, all such first line finders as are idle at this time. From this point on, 55 the operation of the first line finder, the second line finder, the control of the group and final selectors by controlling and registering equipment to extend the calling line through to the called line is accomplished 60 in the manner now obvious.

During the release of the established connection, the marginal relay 709 is energized, provided such connection was a successful one. Relay 709, by attracting its armature, 65 closes a circuit from the positive pole of

battery, armature and contact of said relay, left-hand armature and front contact of the cutoff relay 708 over the upper side of the line through the winding of the operating magnet 700 and the coin 705 to ground. The current in this circuit is sufficient to energize magnet 700 and is of the proper polarity to operate the armature of such magnet in such a way as to collect the coin 705. If, however, the call did not succeed, the controlling sequence switches at the finder switches, on restoring to their normal positions, are not effective to close an energizing circuit for the marginal relay 709. As soon then as the cutoff relay 708 80 releases its armatures and while the slow-to-release relay 707 is maintaining its armature attracted, a circuit is completed from negative pole of battery through the left-hand winding of relay 707, front contact 85 and left-hand armature of such relay, normal left-hand contact of the cutoff relay 708 and thence through the winding of the operating magnet 707 to ground. Current flowing in this circuit is of the proper polarity 90 to operate the magnet 700 in such a manner as to refund the coin.

The method of operation of the system disclosed in the restoration of all engaged apparatus to normal position in the case of 95 premature disconnection, such as that brought about by the calling subscriber abandoning the call prior to the time the called line is tested and seized, in which circumstance no charge should be made against 100 the calling subscriber, will not be described in detail herein, reference being made to the above-mentioned patent to Polinkowsky, No. 1,193,053.

In the above description of the extension 105 of a talking connection from one subscriber's line to another, it was assumed that the called line was one which belonged to an odd hundred and it was therefore located in the second or odd section of the final selector switches. This being true, it was necessary, as has been shown to provide at the register controlling apparatus, some means to distinguish that the called line belonged to an odd hundred, and therefore to 110 arrange for translation such that, when units selection was being made, the brush carriage of the final selector switch would be made to advance the brushes over the first section and into engagement with the 115 terminals of the proper line in the second section of the bank. When a call is made to a line, the hundredths digit of which is even, such line appearing in the first section of the multiple bank of the final selector 120 switches, no translation being necessary, the register controlling equipment is arranged to control the operation of the brush carriage of the final selector, such that the 125 brushes thereof are brought into connection 130

with the proper set of terminals in the first section of the bank. For a detailed description of the operation of the present system in the extension of an untranslated connection, the above-mentioned Polinkowsky patent is referred to.

While the disclosure shows the charging devices on the calling lines to be devices arranged to collect or refund a coin, according 10 as the call is successful or not, it is to be understood that the invention is not so limited. Any desired type of toll apparatus as, for example, message registers may be used which are designed to operate in accordance with the principles of the invention.

What is claimed is:

1. In a telephone system, telephone lines, toll devices, one associated with each line, 20 a plurality of operating means for operating said toll devices, automatic switches for establishing connections between said lines, controlling devices for controlling the selective operation of said automatic switches, 25 and means controlled by said controlling devices for selecting one of said operating means.

2. In a telephone system, telephone lines, toll devices, one associated with each line, 30 a plurality of operating means for operating said toll devices, automatic switches for establishing connections between said lines, controlling devices for controlling the selective operation of said automatic switches, 35 and means controlled by said controlling devices for selecting one of said operating means during the release of an established connection.

3. In a telephone system, telephone lines, toll devices, one associated with each of said 40 lines, a plurality of operating means for operating said toll devices, automatic switches for establishing connections between said lines, controlling devices, one for each of 45 said automatic switches for controlling the selective operation thereof, and means controlled jointly by said controlling devices for selecting one of said operating means.

4. In a telephone system, telephone lines, toll devices, one associated with each of said 50 lines, a plurality of operating means for operating said toll devices, automatic switches for establishing connections between said lines, controlling devices, one for each of 55 said automatic switches for controlling the selective operation thereof, and means controlled jointly by said controlling devices during the release of a connection for selecting one of said operating means to operate said toll devices.

5. In a telephone system, telephone lines, toll devices, one associated with each of said 60 lines, a plurality of sources of current for operating said toll devices, automatic switches for establishing connections be-

tween said lines, controlling devices for controlling the selective operation of said automatic switches, and means controlled by said controlling devices for selecting one of said sources of current to operate said toll 70 devices.

6. In a telephone system, telephone lines, toll devices, one associated with each line, 75 a plurality of operating means for operating said toll devices, automatic switches for establishing connections between said lines, controlling devices, one for each of said automatic switches for controlling the selective operation thereof, and means controlled jointly by said controlling devices for selecting one or another of said operating means dependent upon whether or not the called subscriber answers.

7. In a telephone system, telephone lines, toll devices, one associated with each line, 85 a plurality of operating means for operating said toll devices, automatic switches for establishing connections between said lines, controlling devices, one for each of said automatic switches for controlling the selective 90 operation thereof, and means controlled jointly by said controlling devices during the release of the automatic switches for selecting one or another of said operating means dependent upon whether or not the 95 called subscriber answers.

8. In a telephone system, telephone lines, toll devices, one associated with each line, two sources of current for operating said toll 100 devices, automatic switches for establishing connections between said lines, controlling devices for controlling the selective operation of said automatic switches, and means controlled by said controlling devices for selecting one of said current sources if the 105 called subscriber answers and for selecting the other source if the called subscriber does not answer.

9. In a telephone system, telephone lines, toll devices, one for each of said lines, a plurality of operating means for causing a plurality of different operations of said toll devices, automatic switches for establishing connections between said lines, multi-position 110 controlling switches for controlling the 115 selective operation of said automatic switches, and means dependent upon the position assumed by said controlling switches for selecting one or another of said operating means.

10. In a telephone system, telephone lines, toll devices, one for each of said lines, a plurality of operating means for causing a plurality of different operations of said toll devices, automatic switches for establishing 125 connections between said lines, multi-position controlling switches for controlling the selective operation of said automatic switches, and means dependent upon the position assumed by said controlling switches 130

for selecting one or another of said operating means to operate said toll devices during the release of an established connection.

11. In a telephone system, telephone lines, 5 coin collecting devices associated with said lines, two operating means, one for operating said coin devices to collect a coin and the other for operating the coin devices to refund the coin, automatic switches for establishing connections between said lines, controlling switches for controlling the selective operation of said automatic switches, and means dependent upon the position assumed by said controlling switches in the 10 establishment of a connection for selecting one of said operating means to operate a coin collecting device during release of the connection.

12. In a telephone system, telephone lines, 20 toll devices, one associated with each of said lines, a plurality of operating means for operating said toll devices, automatic switches for establishing connections between said

lines, a sequence switch arranged to be automatically advanced from one position to another to control said automatic switches, and means dependent on the position assumed by said sequence switch for selecting one of said operating means. 25

13. In a telephone system, telephone lines, 30 toll devices, one associated with each of said lines, a plurality of operating means for operating said toll devices, automatic switches for establishing connections between said lines, a sequence switch arranged to be automatically advanced from one position to another to control said automatic switches, and means dependent on the position assumed by said sequence switch for selecting one of said operating means to operate said toll devices 35 during the release of an established connection. 40

In witness whereof, I hereunto subscribe my name this 29th day of April, A. D. 1919.

LIPA POLINKOWSKY.
